UNITED STATES PATENT OFFICE

PAUL SCHUYLER VAN BLOEM, OF GREAT NECK, NEW YORK, ASSIGNOR TO VIKING PRODUCTS CORPORATION, OF NEW YORK, N. Y., A CORPORATION OF NEW YORK

INTERCHANGEABLE-LETTER SIGN

Application filed June 8, 1928. Serial No. 283,952.

An important object of the present invention is to provide an illuminated sign of panel form embodying improved features of construction and assembly.

5 Other objects of the invention will appear hereinafter.

In the drawings:

Fig. 1 is a front elevation of my improved sign;

10 Fig. 2 a vertical section upon a larger scale taken on the line 2—2 of Fig. 1;

Fig. 3 a fragmentary vertical section taken on the line 3—3 of Fig. 2;

15 Fig. 4 a detail vertical section showing a number of assembled sign panels;

Fig. 5 a detail vertical sectional view, upon a larger scale, of one of the panels;

Fig. 6 a detail horizontal section taken upon the line 6—6 of Fig. 5;

20 Fig. 7 a plan view upon a smaller scale of a panel blank;

Fig. 8 a perspective view of one of the character-bearing plates of the sign;

25 Fig. 9 a detail perspective view of another form of plate with an attached character element;

Fig. 10 a vertical section taken through said plate and character element;

Fig. 11 a perspective view of still another 30 form of plate and attached character element;

Fig. 12 a vertical section taken through the plate and element of Fig. 11; and

35 Fig. 13 a vertical section upon a reduced scale showing the sign inverted and of slightly modified form.

40 My improved sign structure includes a flat base molding 1 and a molding 2 in the form of an open, rectangular frame supported by the base molding. The latter is formed with a central longitudinal groove 3 in which the lower side of the frame 2 is fitted and secured in any suitable manner. Mounted within the frame 2 and closing it is 45 an assembled structure which includes a plurality of panels 4 disposed edge to edge and superposed in the same vertical plane. These panels are exactly the same size, shape and construction throughout. Each is 50 formed of sheet metal or other suitable ma-

terial and is rectangular and horizontally elongated in outline. Its end margins are bent rearward to form flat flanges 5; its upper marginal edge is bent rearward to form a flat horizontal flange 6; and its lower marginal edge is bent rearward and then downward to form a flange 7 having a horizontal flat portion 8 of a depth as great as the upper flange 6, and a vertical downwardly extending portion 9. The flanges 6 and 7 both 55 extend along the length of the panel, and the end flanges 5 extend entirely along the length of the panel ends and are disposed between the ends of the flanges 6 and 7. The face area of each panel is formed 60 with a plurality of spaced rectangular apertures 10. In the present instance there are two parallel horizontal rows of these apertures extending along the length of the panel. This arrangement of the apertures may, however, be varied. Extending along the side edges of each aperture are two straight vertical flanges 11 formed by bending the margins of the panel, along the apertures, rearwardly for a slight depth and 65 then inwardly toward each other. The upper and lower ends of the flanges 11 are beveled off as indicated at 12. These flanges are 70 for the purpose of mounting sign characters in the apertures as will be described later in the specification. The entire panel with its various flanges is formed from a single sheet-metal blank shown in Fig. 7.

The frame 2 in the present showing is proportioned to receive two of the panels 4. 75 However these proportions may be varied to accommodate any desired number of panels. The frame 2 is formed, intermediate its fore and aft depth, with a rib 13 which extends along the vertical sides and the top of the frame and projects into the opening defined by the frame. Rearwardly of this rib the frame is formed to provide a countersunk seat 14 with flat walls for the panels 4. One of the two panels is seated in the lower 80 portion of the frame with the flat portion 8 of its lower flange 7 resting upon the lower member of the frame and the depending portion 9 overlapping the rear face of the frame member. The other panel is super- 85 90 95 100

posed upon the first one with the flat horizontal portion of its lower flange 7 resting upon the upper flange 6 of the lower panel and the depending portion 9 of said flange extending down across the rear edge of the flange 6, to effectually seal the joint between the flanges and prevent the escape of light between the panels. The upper flange 6 of the upper panel fits against the top wall of the frame seat 14; the end flanges 5 of the panels fit against the flat side walls of the seat; and the front margins of the panels abut the rib 13 of the frame to dispose the front faces of the panel flush. The walls of the panel seat in the frame extend slightly rearward beyond the side and top flanges 5 and 6 of the panels and small barbs 15 are forced into the frame at the rear edges of said flanges to hold the panels in place.

Each panel carries a light-diffusing glass panel 16 which is spaced back from the rear face of the panel, disposed parallel thereto, and substantially fills the space between the panel flanges. It is held in place by angle strips 17 which are secured to the upper and lower panel flanges 6 and 7 in any suitable manner.

Mounted upon the back of the frame 2 are two lamp casings in the form of sheet metal boxes 18 open at one side. One box is located back of each panel and the open side thereof is substantially equal in area to the panel. Around said open side the box is formed with an outturned flange 19 which abuts the rear face of the frame 2 and the depending portion 9 of the channel flange 7, the latter being so proportioned that said portion 9 is disposed in the plane of the rear face of the frame. The box flange 19 is notched at the edges as at 20 and the depending panel edges 9 are notched as at 21 for engagement with small loop-headed fastening members 22 which are screwed or driven into the frame. The casings 18 are thereby held in place. Mounted in each casing is an electric lamp 23 and the upper and lower walls of the casings are provided with insulation sleeves or eyelets 24 through which circuit wires 25 for said lamps are trained. At their rear edges the casings are formed with beads which contact as at 26.

The apertures 10 of the panels 4 are adapted to be closed by small plates or panels 27 each formed of sheet metal, rectangular in outline and all of the same size. The vertical dimension of each plate is greater than that of the apertures 10. The upper marginal edge of the plate is bent slightly rearward and then upward to form a flange 28 and its lower marginal edge is similarly bent rearward and then downward to form a flange 29 of less depth than the flange 28. The plates are so formed and proportioned 65 with respect to the apertures 10 that they

may be removably mounted therein to close them with the side margins of the plates overlapping the small panel flanges 11 at the sides of the apertures and the flanges 28 and 29 of the plates underlapping the rear face of the panel at the upper and lower edges of the apertures. Each plate may be mounted through the front face of the sign in any one of the apertures 10 by first inserting its upper flange 28 through the upper end of an aperture past the upper beveled edges of the panel flanges 11, swinging the lower end of the plate rearward, and inserting the lower flange 29 of the plate downward past the lower beveled edges 70 of the flanges 11 so that the rearwardly bent portion of the flange 29 rests upon the lower edge of the aperture. The plate is then retained in place by the panel flanges 11 and the plate flanges 28 and 29, the flange 28 75 being proportioned to still remain in engagement with the rear face of the panel when the plate is lowered into position. Each plate when mounted in place is entirely surrounded by overlapping flanges 80 and margins which prevent the escape of light past its edges. To remove a plate it is only required to lift it slightly to free its lower flange 29, swing it outward at the lower end through the front face of the 85 sign, and lower it to free the upper flange 28. Thus all of the plates are readily insertable and removable through the front face of the sign.

All of the plates 27 are of the same size 100 and are interchangeable in all of the apertures 10. In the form of plate occurring in Figs. 1 to 6 inclusive and in Fig. 8 each plate is formed with a character stencil 30 through which the light from the lamps 23 105 shine. This light is first diffused by the glass plate 16 which may be either white or colored. As an alternative light-diffusing or coloring means a thin sheet of transparent or translucent material 31 may be disposed against the back face of each sign plate to cover the stencil 30. This sheet also, may be either white or colored. It may be held in place in any suitable manner. In the present instance it is held against the rear face of the plate by the panel flanges 11 which are bent back just sufficiently to accommodate the superposed plate and sheet and snugly engage the latter. When the sign plates are provided with the 110 sheets 31 the glass plate 16 may be omitted, as indicated in Figs. 5 and 6.

In addition to the character-bearing plates 27 other plates 27^a are provided for closing the apertures 10 at the spaces where no characters are required. The plates 27^a are formed precisely like the plates 27 except that the character stencils are omitted, the face areas of the plates being blank and opaque. These blank plates are inter- 130

changeable with the character plates 27 in all of the panel apertures.

In Figs. 9 and 10 I have shown a character unit of another form. It comprises a sheet metal plate 27^b and an attached glass character plate 32. The latter is adapted to bear against the rear face of the plate 27^b and is formed with a protruding character which is designed to project out through a stencil opening 30^b in the plate. A sign of this character is shown in United States Patent No. 1,311,472 issued to Van Bloem. The stencil plate 27^b is formed precisely like the plates 27 except that it is integrally formed 10 at its upper and lower edges with clips 33 to removably hold the glass character plate in place. These clips are in the form of spring tongues stamped with the sheet metal plate and bent rearwardly and inwardly toward 15 each other to engage the back face of the character plate.

In Figs. 11 and 12 is shown still another form of character unit. It includes a sheet metal plate 27^c formed precisely like the plate 27^b except that the stencil opening is replaced by a relatively large rectangular aperture 30^c which takes up most of the face area. Held at the rear of the plate is a sign comprising an opaque sheet 34 formed with 20 a character stencil opening 35. A backing plate 36 preferably of translucent glass is disposed against the back face of the sheet 34 to appear through the stencil opening, and a glass plate 37 is disposed over the 25 front face of the sheet and bears against the rear face of the plate 27^c upon the margin thereof surrounding the aperture 30^c. The front face of the glass plate 37 is embossed to diffuse light. Such a sign is shown in 30 U. S. Patent No. 1,648,977 issued to Weidner. The sign is held firmly to the plate 27^c by the clips 33^c which engage the backing plate.

Beneath the base molding 1 is a casing 38 which forms a magazine for holding a 40 reserve supply of the small character-bearing and closure plates. This casing is in the form of a sheet metal drawer which is substantially coextensive with the under face of the base and has its upper side edges turned 45 inward as at 39 to engage in longitudinal guide grooves 40 in the sides of the molding, so that the drawer may be opened by relatively sliding it longitudinally. The entire sign is adapted to be inverted as indicated 50 in Fig. 13. When this is done the small sign plates 27 and 27^a must be taken out of the apertures 10 and replaced right side up. The structure permits the sign plates to be mounted equally well in either the upright 55 or the inverted position of the sign frame. In Fig. 13 is also shown a slightly different base structure. The molding 1^a is made ornamental and formed with a countersunk channel 41 to accommodate the drawer 38^a 60 entirely within the molding. The drawer

38^a is formed with outturned flanges which slide in guide grooves formed in the countersunk channel 41 of the molding.

My improved sign structure provides for a wide range of variations in the advertising matter displayed and also in the character and appearance of the advertising matter. These variations may be readily made by the owner of the sign to suit his taste and requirements. Provided with an assembled frame and panel structure, he can easily mount and interchange the small character units in the numerous panel apertures to present the required reading matter for his advertisement. If he needs to change the subject of his advertising he can readily set up new lines of reading matter upon the panels. He can use characters of different styles and also vary the color effects. The sign structure also has the great advantage of simplifying and facilitating the manufacture of signs in a variety of sizes. The panels 4 can be manufactured in a standard size and form. Each panel is formed to assemble and interchange with all of the others of a given size. This is also true of the illuminating means including the lamp casings which can all be made of the same size and form and adapted to fit back of said panels. If, for example, a purchaser requires a sign providing six lines of lettering such a sign can be readily produced by assembling three of the standard panels 4 and three of their companion standard lamp casings in a frame of suitable size, the frame being the only element of the sign which varies with the size. In this manner a sign of any desired size, within reasonable limits, can be easily assembled from stock parts.

While I have shown and described several practicable and very desirable forms of my invention I do not wish to be limited strictly to the disclosure but reserve the right to make such changes as will lie within the scope of the claims.

What I claim is:

1. A display sign comprising a plurality of elongated panels disposed in superposed relation edge to edge in substantially the same plane; means supporting the panels in said relation to form a sign unit; overlapping sealing flanges formed upon said panels along their opposed edges to prevent the passage of light between the panels, each panel being formed with a plurality of apertures in its face; a plurality of character-bearing plates to close said apertures; means to removably hold said character-bearing plates in position to close the apertures in the panels; and illuminating means mounted at the rear of the panels and forming part of the sign unit to illuminate the characters.

2. A panel for a display sign comprising an elongated sheet of stiff material formed with parallel longitudinal edges and having

a plurality of apertures in its face; an integral rearwardly turned flange extending along substantially the length of one of said longitudinal edges; an integral flange extending along substantially the length of the other of said longitudinal edges and turned rearwardly to an extent as great as that of the first flange and then outwardly; and means integrally formed upon the panel at the edges of said apertures to removably hold sign members in the apertures.

3. A panel for a display sign comprising an elongated sheet of stiff material formed with parallel longitudinal edges and having a plurality of apertures in its face; an integral rearwardly turned flange extending along substantially the length of one of said longitudinal edges; an integral flange extending along substantially the length of the other of said longitudinal edges and turned rearwardly to an extent as great as that of the first flange and then outwardly; and flanges integrally formed upon the panel and extending along the sides of said apertures to removably hold sign members in the apertures.

4. A panel unit for a display sign comprising an elongated sheet of stiff, opaque material formed with parallel longitudinal edges and having a plurality of apertures in its face; an integral, rearwardly turned flange extending along substantially the length of one of said longitudinal edges; an integral flange extending along substantially the length of the other of said longitudinal edges and turned rearwardly to an extent as great as that of the first flange and then outwardly; means integrally formed upon the panel at the edges of said apertures to removably hold sign characters in the apertures; and a panel formed of material to admit light carried by said opaque panel and disposed at the back face thereof in register with said apertures.

5. A display sign comprising a plurality of elongated interchangeable panels disposed in superposed relation edge to edge in substantially the same plane; means supporting the panels in said relation to form a sign unit; overlapping rearwardly turned sealing flanges integrally formed upon said panels and extending along their opposed edges to prevent the passage of light therebetween, each panel being formed with a plurality of apertures all of the same size and shape in its face; a plurality of interchangeable character-bearing plates to close said apertures; and retaining means to removably hold the character-bearing plates in place.

6. A panel for a display sign comprising an elongated sheet of stiff material formed with parallel longitudinal edges and having a plurality of apertures in its face; an integral rearwardly turned flange extending

along substantially the length of one of said longitudinal edges; an integral flange extending along substantially the length of the other of said longitudinal edges and turned rearwardly to an extent as great as that of the first flange and then outwardly; and means carried by the panel to removably hold sign members in the apertures.

7. A sign unit for the purpose set forth, comprising a plate formed with a stencil opening defining a sign character and formed with a pair of rearwardly offset edge margins extending respectively along the upper and lower ends of the plate, the upper margin being of greater depth than the lower one; a sheet of material admitting the passage of light disposed against the rear face of the plate and closing the stencil opening; and means carried by the plate to hold said sheet in place.

8. A sign unit for the purpose set forth, comprising a plate formed with a stencil opening defining a sign character and formed with a pair of rearwardly offset edge margins extending respectively along the upper and lower ends of the plate, the upper margin being of greater depth than the lower one; a sheet of material admitting the passage of light disposed against the rear face of the plate and closing the stencil opening; and spring clips carried by the plate to hold said sheet in place.

9. A display sign comprising a plurality of panels disposed in superposed relation edge to edge with their front vertical faces in substantially the same vertical plane; a frame enclosing and supporting the panels in the said relation to form a sign unit, overlapping sealing flanges formed upon said panels along their opposed edges to prevent the passage of light between the panels, each panel being formed in its face with a plurality of apertures of identical form and size; a plurality of identical and interchangeable character-bearing plates to close said apertures; means to removably hold said character-bearing plates in position in said apertures with their front vertical faces substantially flush with the vertical face of the panel; and illuminating means mounted at the rear of the panels and forming part of the sign unit to illuminate the characters.

10. A display sign comprising a plurality of panels disposed in superposed relation edge to edge with their front vertical faces in substantially the same vertical plane; a frame enclosing and supporting the panels in the said relation to form a sign unit, overlapping sealing flanges formed upon said panels along their opposed edges to prevent the passage of light between the panels, each panel being formed in its face with a plurality of apertures of identical form and size; a plurality of identical character-bearing plates to close said apertures and inter-

changeable through the front face of the panel; means to removably hold said character-bearing plates in position in said apertures with their front vertical faces substantially flush with the vertical face of the panel; a light-diffusing panel mounted in each panel back of the character-bearing plates; illuminating means mounted at the rear of each panel; and a casing secured at the rear of each panel and enclosing the 10 illuminating means.

11. A display sign comprising a panel formed with a rectangular face aperture; a character-bearing plate equal in width but slightly longer than said aperture and provided with rearwardly offset flanges extending along its upper and lower edges and adapted to engage the back margins of the panel along the upper and lower edges of the aperture, the body of the plate, between said flanges, being of less height than that of the aperture and the upper flange being of greater depth than the lower one to permit the removal of the plate through the front face of the panel by raising and tilting it forwardly at its lower end; vertical, rearwardly offset flanges carried by the panel and extending along the sides of the aperture to overlap the rear side margins of the character-bearing plate and hold said 20 plate in the aperture with its front face substantially flush with the front face of the panel, said panel flanges and plate flanges cooperating to removably hold the plate in place and prevent the passage of light around its edges.

12. A display sign comprising a panel formed with a face aperture; a character-bearing plate to close said aperture provided with rearwardly offset flanges extending along its upper and lower edges and adapted to engage the back margins of the panel along the upper and lower edges of the aperture, the body of the plate, between said flanges, being of less height than that of the aperture and the upper flange being of greater depth than the lower one to permit the removal of the plate through the front face of the panel by raising and tilting it forwardly at its lower end; vertical, rearwardly offset, parallel flanges carried by the panel and extending along the sides of the aperture to overlap the rear side margins of the character-bearing plate, said panel flanges and character plate flanges cooperating to removably hold the plate in place and prevent the passage of light around its edges, and also providing for the insertion and holding of the plate in place with its character upright and readable 40 when the panel is inverted.

In testimony whereof I hereunto affix my signature.

PAUL SCHUYLER VAN BLOEM.
